W. G. WHITE.

LOG BUNK.

APPLICATION FILED DEC. 27, 1920.

1,424,330.

Patented Aug. 1, 1922.

William G. White, Inventor.
By
Atkins & Steiner, Attorneys.

UNITED STATES PATENT OFFICE.

WILLIAM G. WHITE, OF HOQUIAM, WASHINGTON.

LOG BUNK.

1,424,330.

Specification of Letters Patent. Patented Aug. 1, 1922.

Application filed December 27, 1920. Serial No. 433,255.

To all whom it may concern:

Be it known that I, WILLIAM G. WHITE, a citizen of the United States of America, and resident of Hoquiam, in the county of 5 Grays Harbor, in the State of Washington, have invented certain new and useful Improvements in Log Bunks, of which the following is a specification, reference being had to the accompanying drawing.

10 My invention relates to log bunks, that is to say, to devices that are mounted transversely on a flat car and are provided at their opposite ends with movable chocks, either of which may be tripped from the 15 opposite side of the car so as to release the logs carried by the bunks, by gravity brought to bear through a transverse inclination or dip of the car.

The objects of my invention are to produce improvements in devices of the class 20 described, through which strength, simplicity, economy of construction, and facility of operation may be obtained.

What constitutes my invention will be 25 hereinafter described in detail and succinctly set forth in the appended claims.

In the accompanying drawing,

Figure I is a top plan view, with parts obscured in dotted lines, of one form of 30 embodiment of my invention as applied to a single bunk. The chock at one end of the bunk is shown as elevated, and the one at the other end is shown as depressed.

Figure II is a medial, longitudinal, vertical section of the subject matter of Figure I.

Figure III is a section on the line III—III of Figure II, looking in the direction of the arrows.

Figure IV is a view similar to Figure III, 40 showing a modification of the chock supporting and tripping mechanism, the chock being in said figure shown in the supported position.

Figure V is a top plan view of one end of 45 a bunk, showing the modification illustrated in Figure IV. In this view, the chock supporting position is shown in full lines, and in the tripping position in dotted lines.

Referring to the numerals on the drawing, 50 1 and 2 indicate, respectively, side pieces of an oblong hollow frame which constitutes the bed or bolster of one of my bunks. The side pieces 1 and 2 may be made of any suitable form of metal as, for example, the 55 plates shown provided with angular flanges

3, but any suitable form of plate metal, or of metal fashioned into shape by any suitable means preferred, may be employed.

If the sides 1 and 2 are formed of plate metal, as above described and as illustrated, I 60 prefer to unite them into a single supporting frame or bolster, as by a transverse plate 4 provided upon opposite sides, with skirts 5, riveted or otherwise secured to the plates 1 and 2, respectively. The length of 65 the side pieces 1 and 2 may be varied to suit the transverse extent of the flat car to which they are applicable, and their distance apart, determined by the width of the plate 4, may be varied at will in the sound discretion of 70 the builder.

The plate 4 terminates, at each end, at a distance short of the full extent of the side pieces 1 and 2 sufficient to operatively accommodate a chock 6 that substantially fills 75 the space between the side pieces, one at each end of the plate 4. Each chock is pivotally mounted upon a cross bolt 7, its knuckle 8 being preferably located in close but operative proximity to the end of the 80 plate 4. The end of the chock 6 opposite the end of the knuckle 8 is bent in the form of a knee, below which the leg 10 depends. Between lugs 11 that are provided upon the end of the side pieces 1 and 2, upon a cross 85 bolt 12, is pivoted a supporter 15 which is adapted to be swung upon the bolt 12 in the path of the leg 10, so as to support the chock in a position elevated above the top of the bunk as shown at the left in Figure II, or 90 to drop it below the top of the bunk as shown at the right in Figure II. Upon the removal of the support for the leg 10, the chock drops, with pivotal action upon its bolt 7, until its downward swing is arrested 95 by obstruction.

The sweep of the leg 10 is in close approximation to the cross bolt 12, so that there is a minimum leverage imposed upon the supporter 15, while it is in the chock- 100 supporting position.

As is well understood in the art relating to bunks, the chocks, being designed to discharge their load through gravity by depression of one end of the bunk, must be operated from the upper end of the bunk, that is to say, from the end remote from the discharge end of the bunk. To that end, I prefer to employ a bell crank lever 16 pivoted at its angle, as indicated at 17, to the flange 3. 110

The short end of the lever 16 is pivoted, as indicated at 18, to a link bar 19, whose end opposite that indicated at 18 is pivoted as indicated at 20 to a roller 21 working in 5 opposite oblong guide-ways 22 provided for it in the respective side pieces 1 and 2. The roller 21 is preferably provided at its opposite ends with heads 23 by which it is confined within the guide-ways 22. A brace 10 rod 24 is secured, as indicated at 25, to the link bar 19, and is pivotally secured, as indicated at 26, to the roller 21. The co-operation of the link bar 19 and the brace rod 24 imparts a true movement to the roller 21 in 15 its guide-ways through manipulation of the bell crank lever 16. In Figure I, one of the levers 16 is shown in position to retract its roller 21 from underneath the supporter 15 to which it is appropriated, while the other 20 is shown in position to hold its supporter in the horizontal or chock-supporting position.

In Figures I to III, inclusive, is shown the roller 21 as above described. In the remaining figures, I illustrate a modified 25 means for sustaining the supporter 15. In those last named figures 30 indicates a rod, pivoted at one end to a bracket 31 on one side piece of the bunk, and having its other end extending through a slot similar to 22 30 in Figure II in the other side piece, within which it may oscillate, between limits fixed by the length of the slot, under impulse imparted through a member equivalent to the link bar 19. The rod 30 preferably carries a roller or buffer 33 upon which, when the rod 30 is disposed at right angles to the bunk sides 1 and 2, as shown in full lines in Figure V, the supporter 15 is sustained in horizontal position, but which, when the 40 rod is swung upon its bracket 31 as shown in dotted lines in Figure V, releases the supporter 15 and allows it to drop to the vertical.

The operation of my device will be readily understood by one skilled in the art from the 45 brief description thereof which follows. Assuming that a flat car, not shown, is equipped with my bunks, disposed in pairs, they are supposed to carry a load of logs laid across them, lengthwise of the car, the 50 logs being held in place on the bunks by the chocks 6 which are in the elevated position shown at the left in Figure II. If now the car be tilted to one side or the other, the logs will tend by gravity to roll off the bunks, 55 and may do so when the lowermost chocks are tripped, an operation that may be accomplished by pulling out the long arms of the levers 16 which control said chocks, and which, as has been already specified, are disposed upon the uppermost side of the car, out of the way of danger to an operator by the released logs. After each chock 60 tripping operation, upon discharge of the

logs, the chock is again set by hand, and the bunk is again ready for service.

65

What I claim is:

1. In a log bunk, the combination within an oblong hollow frame, of a pivoted chock hung horizontally therein and substantially filling the space between the sides of said 70 frame, a supporter, also pivoted to the frame within reach of the sweep of the chock, and manipulative means adapted to sustain or release the supporter at will.

2. In a long bunk, the combination within 75 an oblong hollow frame, provided with a pair of separated transverse bolts, of a chock pivoted to one bolt, a supporter pivoted to the other bolt in operative reach of the free end of said chock, and manipulative 80 means adapted to sustain or release the supporter at will.

3. In a log bunk, the combination with an oblong hollow frame, of a pivoted chock hung horizontally thereon, a supporter, also 85 pivoted to the frame within reach of the sweep of the chock, and manipulative means adapted to sustain or release the supporter at will, said means comprising a member slidably mounted in the frame and movable 90 into and out of engagement with the supporter.

4. In a log bunk, the combination with an oblong hollow frame, of a pivoted chock hung horizontally thereon, a supporter, also 95 pivoted to the frame within reach of the sweep of the chock, and manipulative means adapted to sustain or release the supporter at will, said means comprising a roller movably mounted in the frame.

5. In a log bunk, the combination with an oblong hollow frame, of a pivoted chock hung horizontally thereon, a supporter, also pivoted to the frame within reach of the sweep of the chock, and manipulative means 105 adapted to sustain or release the supporter at will, said means comprising a roller movably mounted in slots in the frame.

6. In a log bunk, the combination with an oblong hollow frame, of a pivoted chock 110 hung horizontally therein, a supporter, also pivoted to the frame within reach of the sweep of the chock, and manipulative means adapted to sustain or release the supporter at will, said means comprising a roller movably mounted in the frame and operatively actuated to release or sustain the supporter by a bell crank lever pivoted to the frame at its angle.

In testimony whereof, I have hereunto set 120 my hand in the presence of two subscribing witnesses.

WILLIAM G. WHITE.
